UNITED STATES PATENT OFFICE.

ASHLEY F. WARD, OF BOSTON, MASSACHUSETTS, ASSIGNOR TO THE A. F. WARD MACHINERY CO., OF BOSTON, MASSACHUSETTS, A CORPORATION OF MASSACHUSETTS.

DESIGN FOR A LOAF OF BISCUIT.

49,942.

Specification for Design.

Patented Nov. 21, 1916.

Application filed February 19, 1915. Serial No. 9,460. Term of patent 14 years.

To all whom it may concern:

Be it known that I, ASHLEY F. WARD, a citizen of the United States, residing at Boston, in the county of Suffolk and Commonwealth of Massachusetts, have invented a new, original, and ornamental Design for a Loaf of Biscuit, of which the following is a specification, reference being had to the accompanying drawing, forming part thereof.

Figure 1 is a perspective view; Fig. 2 is a

top plan view; Fig. 3 is a bottom plan view; showing my new design.

I claim:

The ornamental design for a loaf of biscuit, substantially as shown.

ASHLEY F. WARD.
